UNITED STATES PATENT OFFICE

125,614

DESIGN FOR AN APPAREL RACK OR THE LIKE

Bernard M. Flannery, Galion, Ohio

Application December 23, 1940, Serial No. 97,577

Term of patent 14 years

To all whom it may concern:

Be it known that I, Bernard M. Flannery, a citizen of the United States, residing at Galion, in the county of Crawford and State of Ohio, have invented a new, original, and ornamental Design for an Apparel Rack or the like, of which the following is a specification, reference being had to the accompanying drawing, forming part thereof.

I claim:

The ornamental design for an apparel rack or the like, as shown.

BERNARD M. FLANNERY.
